UNITED STATES PATENT OFFICE.

CHARLES W. GRAHAM, OF ROME, NEW YORK, ASSIGNOR TO AMERICAN CAN COMPANY,
A CORPORATION OF NEW JERSEY.

AUTOMATIC STOP-MOTION FOR CAN-BODY-FORMING MACHINES.

1,154,244.

Specification of Letters Patent. Patented Sept. 21, 1915.

Application filed January 23, 1910. Serial No. 540,568.

To all whom it may concern:

Be it known that I, CHARLES W. GRAHAM, residing at Rome, in the county of Oneida, State of New York, have invented certain new and useful Improvements in Automatic Stop-Motions for Can-Body-Forming Machines, of which the following is a specification.

This invention relates broadly to an automatic stop mechanism, and is herein disclosed as applied to can making machinery.

One of the objects of the invention is to provide new and improved means for instantly stopping the action of an element under given conditions, by disrupting the operative connection between said element and a constantly moving part which actuates it.

A further object is to accomplish such a disruption automatically, and preferably by electro-mechanical means of such construction and arrangement that its action shall be rapid and certain, and yet without undue multiplication of parts and functions.

Still another object is to bring about such disruption by means including a constantly moving part normally out of operative relation to the element whose movement is to be stopped, and a movable member normally out of operative relation to the constantly moving part and said element, automatically operative, preferably electrically controlled, means for allowing movement of the movable member into such operative relation; and means for moving it out of such relation again.

A more specific object of the invention is to provide can making machinery with means attaining the above and other desirable ends, and to devise mechanism wherein the operation of blank feeding means may be instantly and automatically stopped upon the happening of a given circumstance.

I also aim to provide a device in which interruption of the feed is automatically brought about through the intermediary of electrically controlled means whose operation is determined by that of the feeding means, and by a characteristic, such as given thickness, of the material or blank fed.

Other objects and aims, more or less broad than those stated above, will be in

part obvious and in part specifically adverted to in the course of the following detailed description, in which the elements, combinations, and arrangements of parts constituting the invention are set forth, and the scope of the application thereof indicated in the appended claims.

In the accompanying drawings, which are to be taken as a part of this specification, and in which I have shown merely preferred forms of embodiment of the invention and the various contributing devices; Figure 1 is a rear elevation of a can making machine embodying my invention; Fig. 2 is a sectional plan view on the line 2—2 of Fig. 3; Fig. 3 is a vertical section on the line 3—3 of Fig. 1; Fig. 4 is a side elevation taken at right angles to the view of Fig. 1, the casing being partly broken away; Fig. 5 is a detail sectional plan of part of the clutch operating means; Fig. 6 is a detail of the manually operated means for returning the gravity member to normal position; Fig. 7 is a side elevation, partly sectional and partly schematic, illustrating the mechanism and electrical connections for controlling the gravity member; and Fig. 8 is a section on the line 8—8 of Fig. 7.

Referring to the drawings, wherein is illustrated a machine embodying the above and other features of my invention, there is shown a frame comprising broadly a base 1, upon which are erected various standards which support the driving shafts of various operative parts, constituting a can body making machine, said standards being preferably formed integral with the base portion as shown.

The various operative parts of the machine are driven from the main drive shaft 2, which extends transversely of the machine near the central portion thereof, journaled in bearings carried by suitable standards 3 and 4, and provided exteriorly of the machine with the pulley 5, which may be driven from any suitable source of power. Main drive shaft 2 is provided with the worm wheel 6, which meshes with the worm wheel 7 loosely mounted upon a secondary shaft 8.

9 indicates a bevel gear fixed upon shaft 8, and 10 a clutch member slidably mounted on the rear end of said shaft for recipro-

catory movement by means of a pin and slot connection, not referenced. A bifurcated clutch-lever or shipper-fork 11 straddles the member 10 which is keyed to the shaft 8, the bifurcated ends of the lever being provided with anti-friction rollers 12 that engage a circumferential groove 13 of the member 10. Obviously, by moving the lever 11 the clutch end 14 of the member 10 may be moved into or out of engagement with a correspondingly shaped member 15 fast to the constantly rotating worm wheel 7, with the effect of positively driving the gear 9 and shaft 8 or not, as desired. Gear 9 being fast on the forward end of the shaft 8, by its engagement with bevel gear 16 drives an upright shaft 17, journaled in a standard 18, that drives, through the intermediary of an epicycloid gear 19, a reciprocating blank feeder 21 (see Figs. 1 and 3). The blank feeder 21 has a depending enlargement 23 provided with a bore adapted to receive a guiding member 24 on which the depending portion reciprocates back and forth. This reciprocating movement is derived from the internal epicycloid gear 19 by means of a pinion, 191, mounted on an arm 192, pivotally secured to an extension 193 on the depending portion 23 of the carrier 21. The slide 21 is provided with a plurality of spring-controlled feed fingers or dogs 22, arranged in the usual manner for feeding blanks through the machine step by step. The opposite end of shaft 8 operates, as by means of eccentrics 20 and 23 and various connected parts, the bending members not shown, which are adapted to bend the edged blanks about the horn 28, which rests against a yoke 29 located centrally of the machine. Shaft 8 also drives as by means of the crank 31 the bumping mechanism 32 employed to jam the interlocked flange portions of the can body against horn 28. A worm wheel 33, driven from a worm gear 34 on shaft 8, actuates a shaft 35 suitably journaled in the frame parallel to shaft 2, which carries at its opposite ends eccentrics 36, through which are actuated edging devices 37. There is also mounted on shaft 35 a sprocket wheel 38, which drives, by means of chain 39, a sprocket wheel 40, mounted on a shaft 41 suitably journaled in the machine frame parallel to shaft 2, but on the other side thereof from shaft 35. Shaft 41 actuates eccentrics 42 at opposite ends thereof, through which are operated the notchers 43. 44 indicates a crank on the end of shaft 8, exteriorly of the machine, which, through connections 45, 46 and 47 reciprocates the horn expander 48.

A mechanism denoted by 49 mounted upon the top portion of the machine is adapted to maintain the blanks flatwise against the bed or table 50.

The blank feeder 21 extends across the machine past notching devices 43, edging devices 37, and to horn 28 and bumper 32, and by its reciprocation is adapted, in a manner well understood, to progress a blank to each of said operating mechanisms in turn. For the purposes of these mechanisms it is expedient that only one blank at a time be presented to any one of them, and that said blank should be of proper thickness. Therefore I provide a means which, when too many blanks or an improper blank may be accidentally or otherwise presented, will immediately act to stop the feed, thus preventing the possibility of damage. To this end I provide at the front end of the machine, suitably spaced above the table 50 of the machine, a member which, through intermediate devices, will stop the action of the feeding device by disrupting the operative connection between the feeding means and the counter shaft, through movement of the clutch that connects them. The control for said disrupting means in the present invention being electrical, the said member takes the form of a contact piece 51, carried in a housing 52, and pivoted at its lower end, as indicated at 53. The lower end of member 51 carries a part that extends forwardly of the machine, preferably provided with a roller 54, carried on an eccentric screw 55, held by set screw 56, whereby the roller may be secured in desired vertical adjustment. A stem 57 extends upwardly into the housing, and is provided with electrically connected contacts 58, 59, adapted to engage respectively contacts 60, 61, insulatedly mounted in the back of the housing, and forming the terminals of a circuit "C", diagrammatically indicated in Fig. 7. A spring 62 on the housing bears against the member 51 to hold the contacts 58, 59, normally separated from contacts 60, 61, and keep the roller 54 projected slightly below the housing, as shown in Fig. 7.

63 indicates a stop piece for the member 51, which may be adjustable to regulate the amount of possible projection of roller 54. Normally the roller projects to such an extent that a blank of proper thickness may pass between it and the table, and so that if more than one blank, or a too thick blank, is presented, the roller will be engaged thereby and forced back and up to close the circuit referred to, with effects hereinafter described.

The clutch lever 11 is fast on a rock-shaft 64 that is pivoted on a bracket 65 on the machine frame, so that rotative movement of the said rock-shaft will cause movement of the clutch lever. Such rotative movement of the rock-shaft is brought about automatically by means of an arm 66, which is adapted to be operated from a moving part of the

machine when the circuit "C" is closed. For manual control of the clutch, the rock-shaft may be provided with a handle 67. 68 indicates an eccentric upon the shaft 17, 5 and 69 an eccentric rod, provided at its outer end with a wrist-pin 70 that engages a block 71 slidable in a way 72 on a bracket 73 fast to the machine frame. The arrangement of parts is preferably such that the path of re- 10 ciprocation of block 71 is alined with arm 66, though these parts are normally physically disjunct. It is obvious that if a connecting member be interposed between block 71 and arm 66, to transmit the movement of the 15 former to the latter, the clutch may be operated to disconnect the gear 7 from the shaft 8. Such connecting means preferably takes the form of a gravity member 74, which may include a rod 75 slidable and 20 adapted to be held in a sleeve 76 suitably secured to the end frame of the machine. Adjacent its upper end the rod 75 is provided with an upwardly tapering portion 77, terminating in an abrupt shoulder 78, with 25 which is adapted to engage the end of a finger 79, that is pivoted outside the sleeve and spring-pressed so that a portion 81 thereof extends through an aperture 82 in the sleeve, to engage the rod 75. When the rod is slid 30 upwardly a sufficient distance, the end of part 81, which is shaped conformably with the taper 77, will engage with the shoulder 78, and thus hold the rod in uplifted position. The finger 79 constitutes the armature of an electro-magnet 83 that is mounted 35 on a bracket insulatedly secured to sleeve 76, the coils of said magnet being included in the circuit "C," so that when said circuit is closed the member 79 will be moved against 40 the pressure of its spring to withdraw the portion 81 from engagement with shoulder 78, thereby permitting the rod 75 to slide downwardly in its sleeve by gravity.

Secured to the lower end of rod 75 is a 45 piece 84, provided with a bore in which is slidable a member 85, which may have a collar 86 to limit its sliding movement in one direction. Pivotal movement of rod 75 within its sleeve is prevented by the engagement with a slot 87 in arm 66 of a pin extension 88 on member 85, said pin moving vertically in the slot as rod 75 moves.

89 indicates a support for the piece 84, which limits the downward movement of rod 55 75, and which may be pivoted on the bracket 73 and provided with a handle 90, by the manipulation of which the rod may be moved up into renewed engagement with finger 81.

The parts are so disposed that the member 60 85, when the rod 75 has reached its limit of downward movement will be in the line of movement of block 71, and extending longitudinally between the latter and the clutch-lever arm 66; and member 85 is of such 65 length that when block 71 is at the inward

limit of its stroke, as shown in Fig. 5, it will contact one end of member 85 and slide it within the bore of piece 84 to contact and move the arm 66, supposing the latter to be in the position shown in Fig. 1, which is its 70 position when the gear 9 is driven by the counter-shaft and the blank-feeding means operating.

In the operation of the device, if the feeding device moves a blank along the table 75 that is too thick to pass between the table and the roller 54 without moving the latter, or if two blanks are presented, the member 51 will be moved on its pivot to close the circuit "C," in the manner described. The 80 closing of said circuit energizes the magnet 83, whereupon the finger 81 is moved out of engagement with the rod 75, allowing the rod to slide downwardly in its sleeve, whereby the member 85 is brought to the position 85 which the relative approach of the block 71 to arm 66 may constitute it a connecting member between them, so that the rock-shaft 64 will be actuated to move the clutch, whereby to break the operative relation between the shaft 8 and the constantly driven gear 7, thereby stopping the machine.

It will be observed that the operation of the stopping means is particularly rapid and certain, involves but few parts, and the 95 very simplest mechanical functions.

I desire it understood that I do not limit my claims by the details of construction shown, in which I have simply illustrated one way of embodying the creative part or 100 conception of the invention in concrete form in a structure or machine. The described devices are simply embodiments of the invention which other structures might embody, and some of the parts, as also combinations 105 of parts, might well be used without the others in different types of such machines, without departure from the purview of my invention; and I regard myself as entitled to such variations from the shown and described devices as fall within the scope of 110 my invention as indicated in the claims. It is also to be understood that materials, sizes, and relativities of parts are unimportant, except as they are specified in the claims. 115

Having thus described my invention what I claim as new and desire to secure by Letters Patent is:

1. In a machine of the character described, in combination: a constantly moving part; 120 a blank feeding means; a clutch connection between said part and the feeding means; a lever for moving the clutch into and out of operative position; a second moving part; a gravity member adapted to establish operative connection between said clutch moving lever and said second moving part; devices for holding the gravity member normally out of operative position; and automatically operative, electrically controlled means for 125 130

operating said devices to release the gravity member to cause the latter to establish operative connection between said second moving part and the clutch moving lever, the 5 operation of said means being dependent upon that of the feeding means, substantially as specified.

2. In a machine of the character described, in combination: a constantly moving part; 10 a blank feeding means; a clutch connection between said part and the feeding means; a lever for moving the clutch into and out of operative position; a second moving part; a gravity member adapted to establish operative connection between said clutch moving lever and the second moving part; devices for holding the gravity member normally out of operative relation; and automatically operative means controlling said devices and adapted to operate the latter to thereby release and permit the gravity member to establish operative connection between said second moving part and the clutch moving lever, the 20 operation of said automatically operative means being dependent upon that of the feeding means, substantially as specified.

3. In a machine of the character described, in combination: a constantly moving part; 30 a blank feeding means; a clutch connection between said part and the feeding means; a lever for moving the clutch into and out of operative position; a second moving part; a gravity member adapted to establish operative connection between said clutch moving lever and said second moving part; devices for holding said gravity member normally out of operative relation; and means governing the movements of said devices, 35 substantially as specified.

4. In a machine of the character described, in combination: a constantly moving part; a blank feeding means; a clutch connection between said part and the feeding means; 45 means for moving the clutch into and out of operative position; a reciprocating member; a gravity member adapted to establish operative connection between said clutch moving means and said reciprocating member; devices for holding said gravity member normally out of operative relation; and electrically controlled means adapted to operate said devices to thereby release the gravity member and permit the latter to establish operative connection between said reciprocating member and the clutch moving means, the operation of said electrically controlled means being dependent upon that of the feeding means, substantially as specified.

5. In a machine of the character described, in combination: a constantly moving part; a blank feeding means; a clutch connection between said part and the feeding means; means for moving the clutch into and out of operative position; a second, normally, 60

constantly moving part; a gravity member adapted to establish operative connection between said clutch moving means and said second moving part; devices for holding said gravity member normally out of operative relation; and automatically operative means controlling said devices and adapted to operate the latter and thereby release the gravity member and permit the latter to establish operative connection between said second moving part and the clutch moving means, substantially as specified.

6. In a machine of the character described, in combination: a constantly moving part; a blank feeding means; a clutch connection between said part and the feeding means; means for moving the clutch into and out of operative position; a second, normally constantly moving part; a gravity member adapted to establish operative connection between said clutch moving means and said second moving part; devices for holding said gravity member normally out of operative relation; and automatically operative means controlling said devices and adapted to operate the latter and thereby release the gravity member and permit the latter to establish operative connection between said second moving part and the clutch moving means, the operation of said automatically operative means being dependent upon that of the feeding means, substantially as specified.

7. In a machine of the character described, in combination: a constantly moving part; a blank feeding means; a clutch connection between said part and the feeding means and movable into and out of operative position; a second moving part; a gravity member adapted to establish operative connection between said clutch and the second moving part; devices for holding the gravity member normally out of operative relation; and automatically operative means governing the movements of said devices and adapted to operate the latter to thereby release the gravity member and permit the same to establish operative connection between said second moving part and the clutch, the operation of said automatically operative means being dependent upon that of the feeding means, substantially as specified.

8. In a machine of the character described, in combination: a constantly moving part; a blank feeding means; a clutch connection between said part and the feeding means; a bell crank lever for moving the clutch into and out of operative position; a second moving part; a gravity member adapted to establish operative connection between said bell crank lever and said second moving part; devices for holding said gravity member normally out of operative relation; and automatically operated, electrically controlled means governing said de-

5 vices and adapted to move the latter to thereby release said gravity member, the operation of said automatically operative means being dependent upon that of the feeding means, substantially as specified.

9. In a machine of the character described, in combination: a constantly moving part; a blank feeding means; a clutch connection between said part and the feeding means; a bell crank lever for moving the clutch into and out of operative position; a second moving part; a gravity member adapted to establish operative connection between said bell crank lever and the second moving part; devices for holding said gravity member normally out of operative relation; and automatically operative means governing said devices and adapted to cause movement of the latter to thereby release the gravity member and permit the same to establish operative connection between said moving part and the bell crank lever, substantially as specified.

10. In a machine of the character described, in combination: a blank feeding means; a shaft; a gear connected with the feeding means; a clutch adapted to throw said gear into and out of rotative relation with said shaft; means for moving the clutch; an element driven from the shaft in alinement with the clutch moving means but normally unconnected therewith; a slideable member adapted to be interposed and form an operative connection between said element and said clutch moving means; and means permitting said sliding member to be interposed between said element and the clutch moving means to thereby disrupt the operative relation between the shaft and gear, substantially as specified.

11. In a machine of the character described, in combination: a blank feeding means; a shaft; a gear connected with the feeding means; a clutch adapted to throw said gear into and out of rotative relation with said shaft; means for moving the clutch; an element driven from the shaft in alinement with the clutch moving means but normally unconnected therewith; a slideable member adapted to be interposed and form an operative connection between said element and said clutch moving means; and automatically operative means permitting said sliding member to be interposed between said element and the clutch moving means to thereby disrupt the operative relation between the shaft and gear, substantially as specified.

12. In a machine of the character described, in combination: a blank feeding means; a shaft; a gear connected to said feeding means; a clutch adapted to throw said gear into and out of rotative relation with said shaft; means for moving the clutch; an element driven from the shaft in

alinement with the clutch moving means, but normally unconnected therewith; a gravity member adapted to be interposed and form an operative connection between said element and said clutch moving means; a sleeve 70 in which said gravity member is slideable; devices for holding the gravity member in an elevated position; means for retracting said holding devices to thereby permit the gravity member to slide downwardly in the 75 sleeve and assume its interposed relation between said element and the clutch moving means; and manually operative means for moving said clutch, substantially as specified.

13. In a machine of the character described, in combination: a continuously moving part; mechanism for feeding sheets; means for operatively connecting said part with said mechanism; a member for moving 85 said means into and out of operative relation between said part and said mechanism; a second moving part operatively connected with the first named moving part; an element adapted, when in one position, to establish operative connection between said member and said second moving part and arranged to assume such position except when prevented from so doing; normally stationary means for preventing said element from assuming said position; and automatically operative means including a normally stationary magnet for operating said preventing means to cause the latter to release said element to thereby establish operative connection between said second named moving part and said first named means.

14. In a machine of the character described, in combination: a constantly moving part; feeding means normally coöperative with said part; and means for disrupting said relation, said means including a second part constantly movable under normal conditions of the feeding means, a member normally held stationary and movable into operative position relatively to said second named part, and devices controlling the position of said movable member, substantially as specified.

15. In a machine of the character described, in combination: a constantly moving part; feeding means; a clutch connection between said part and the feeding means and movable into and out of operative position; a second moving part; a member, 110 normally held immovable, adapted to establish operative connection between said clutch and said second moving part; and means normally holding said member stationary and out of operative position and adapted to release the same when abnormal conditions occur in the feeding means, substantially as specified.

16. In a machine of the character described, in combination: blank feeding 130

mechanism; two normally disjunct movable members; a constantly moving part coöperating with one of said members; a clutch connected with the other of said members and adapted to establish coöperative relation between the constantly moving part and the feeding mechanism; a third member normally held in a fixed position and unconnected with said first named members; and 10 electrically controlled means adapted to permit said third named member to be opera-

tively interposed between said first two members to thereby break the operative connection between said constantly moving part and the feeding mechanism, substantially as 15 specified.

In testimony whereof I affix my signature in the presence of two witnesses.

CHARLES W. GRAHAM.
